UNITED STATES PATENT OFFICE.

LOUIS C. WHITON, OF NEW YORK, N. Y., ASSIGNOR TO PRAT-DANIEL CORPORATIONS,
OF NEW YORK, N. Y., A CORPORATION OF NEW YORK.

HEAT EXCHANGER.

Application filed July 25, 1924. Serial No. 728,103.

In a patent of Prat No. 1,409,967 of March 21, 1922, there is described a heat exchanger made of plates mounted side by side and spaced apart with openings arranged in such a way that the heating fluid and the heated fluid pass through alternate spaces.

In the said patent, the spacers between the plates consist of coil springs or the like which permit the passage of a fluid and which at the same time secure tight joints.

My invention provides a heat exchanger of the same type and which permits the use of heating fluids having higher temperatures than can be used with a coil spring spacer. The accompanying drawings illustrate embodiments of the invention.

Fig. 1 is a side elevation and Fig. 2 is a plan of corner portions;

Fig. 3 is a separate detail of one of the members of Fig. 1;

Fig. 4 is a side elevation of the same;

Figs. 5 and 6 are edge elevations of other styles of spacer;

Fig. 7 is a sectional view illustrating the use of the spacer of Fig. 6;

Fig. 8 is a face elevation of the arrangement shown in Figs. 1 and 2.

Referring to the embodiment of the invention illustrated, the plates which separate the passages are indicated at 1, 2, 3 and 4. Between the top and bottom edges of the plates 1 and 2 the space is closed by plates 5. The same arrangement is provided for the top and bottom of the spaces between the plates 3 and 4. The alternate spaces, for example, that between the plates 2 and 3, are open at the top and bottom and closed at the front and back by plates 6.

At their open edges the plates are held in position by spacers which at the same time permit the free passage of the fluids. According to Figs. 1 to 4, each spacer comprises a pair of narrow plates or bars 7 with cross pieces or struts 8 between them at intervals, welded or riveted to the bars 7.

The plates and spacers thus assembled are held against lateral movement by any usual or suitable frame and are pressed against

each other endwise by means of two sets of 50 heavy springs, one at each end of the assemblage. Or a solid abutment may be provided at one end and a single set of springs at the opposite end.

A number of compression springs 9 are 55 arranged to bear against the end plate 4 in line with the cross pieces 8 of the spacing elements. A bar 10 bears against the outer ends of said springs and is pressed forward by means of adjusting screws 11 60 threaded through a fixed bar 12 constituting part of the surrounding frame. By the provision of a similar spring arrangement at the opposite end, the plates and spacers are held firmly in position. 65

The shapes of the plates, and the location of the openings at their edges, and consequently the direction of flow of the fluids may be considerably varied; several different arrangements being shown in the Prat 70 patent above referred to. Also various other spring arrangements may be provided, and various styles of spacing elements.

According to Fig. 5, a pair of plates 2 and 3 are spaced apart by separate short spacers 75 or struts 13 arranged to fit between the plates and provided with flanges 14 bearing against the edges of the plates.

According to Figs. 6 and 7, the plates are held apart on their open edges by channel 80 formed spacers or struts 15 which bear directly against the faces of the plates and extend outward beyond the edges of the plates, where they are held in proper relative positions by means of bars 16 fastened 85 to opposite faces of their projecting portions with bolts 17.

The arrangement described is economical in construction and permits the use of high temperature fluids since the springs are 90 placed outside of the fluid passages.

Though I have described with great particularity of detail certain embodiments of the invention, yet it is not to be understood therefrom that the invention is restricted to 95 the particular embodiments disclosed. Various modifications in detail and in the arrangement of the parts may be made by

those skilled in the art without departing from the invention as defined in the following claim.

What I claim is:

5 A heat exchanger for fluids formed of plates with spacers between the open edges of said plates and with springs bearing

against at least one of the end plates of the assemblage to press the parts together, said spacers comprising struts connected together ¹⁰ in proper relative positions.

In witness whereof, I have hereunto signed my name.

LOUIS C. WHITON.
